UNITED STATES PATENT OFFICE.

JOHAN GEORGE HEHR, OF PITTSBURG, PENNSYLVANIA.

BOTTLE-WASHING MACHINE.

SPECIFICATION forming part of Letters Patent No. 685,138, dated October 22, 1901.

Application filed August 28, 1900. Serial No. 28,267. (No model.)

To all whom it may concern:

Be it known that I, JOHAN GEORGE HEHR, a citizen of the United States, residing at Pittsburgh, in the county of Allegheny and State 5 of Pennsylvania, have invented or discovered new and useful Improvements in Bottle-Washing Machines, of which the following is a specification.

In the accompanying drawings, which make 10 part of this specification, Figure I is a vertical section on line I I of Fig. III. Fig. II is a detail view, partly in section, showing the springs and double cam. Fig. III is a vertical section on line III III of Fig. I. Fig. IV 15 is a detail view of the levers for operating the bottle and pipe raising cams.

The object of my invention, generally stated, is to provide means for the economical and expeditious scrubbing, washing, and rinsing 20 of bottles or similar articles.

1 represents a stationary tank, having lid 2 and foot-rests 3 3. 25 4 is a revolving frame, having lid 5 and hubs 6 6, said hubs being secured to hollow shaft 7 by means of set-screws 6' 6'. 8 8 are racks resting on lugs 8' 8'.

9 9 are bottles resting in the compartments 28 8' of the crates 8 8. 10 10 are spring or elastic packers secured 30 to the lid 5 and pressing on the bottoms of bottles 9 9.

11 11 are shot-holders flared outwardly at their mouths 11' 11'.

11² 11² are perforations in the shot-holders, 35 through which the water can escape. These perforations are smaller than the diameter of the shot 12.

11³ 11³ are sleeve projections acting as guides for the water-exit pipes 13 13.

40 14 14 are guides for shot cut-off valves 15 15, said valves having ports 15' 15'.

16 16 are levers moving in the slots 15² 15² and operating the valves 15 15. These levers are secured to shaft 17, said shaft having its 45 bearings in the sides of the revolving frame 4.

17' is a lever-handle attached to the end of shaft 17, by which the valves 15 15 are opened and closed.

18 18 are branch supply-pipes feeding wa- 50 ter to exit-pipes 13 13 and receiving their source of supply from hollow shaft 7 by means of flexible tubular connections 19 and pipe 20.

21 is a lever-bar pivotally attached to one side of revolving frame 4 by means of bolt 21'.

22 22 are side lever-arms pivotally connected to the lever-bar 21 above its axis and secured to crank-arms 23 23 at their outer ends. The crank-arms 23 23 are keyed to shafts 24 24. Keyed also to shafts 24 24 are cranks 25 25. Pivotally connected to their 60 outer ends by bolts 25' 25' are hangers 26 26. These hangers 26 26 raise and lower the pipes 18 18 and their connections. Under the pipes 18 18 and secured to the hangers 26 26 are supports 27 27, on which the pipes 18 18 rest. 65

27' 27' are pins for forcing the pipes down.

Secured to one end of stationary tank 1 by means of flanges 28' 28' and bolts 28² 28² is frame 28. Double cam 29 is bolted to frame 28 by means of bolts 29' 29'.

30 is a collar projection of double cam 29.

31 and 31' are respectively a loose and keyed pulley.

32 is a buffer-spring.

33 is a collar secured to the hollow shaft 7. 75

34 34 are rollers for reducing the friction in the longitudinally-reciprocating movement of the hollow shaft 7.

35 is a check-collar.

36 is a spiral spring for forcing the single-faced cam 37 into the serrations 29³ of the double cam 29. Said cam 37 is keyed on shaft 7.

38 is a loose coupling for connecting the stationary pipe 39 and the hollow shaft 7. 85

To operate my invention, catches 40 and 41 of lids 2 and 5 are opened and the lids 2 and 5 are raised and turned back on their hinges 42 and 43. The racks 8 8, containing bottles 9 9, are lowered onto projections 8' 8', while 90 the heads of the bottles 9 9 rest in the mouths 11' 11' of the shot-holders 11 11. The bottles now being in position in the revolving frame, lid 5 is then brought down and fastened by means of latch 40 pressing the springs or 95 other elastic packers 10 10 down on the bottoms of bottles 9 9, thereby holding the bottles 9 9 steady during the operation of scrubbing the interior and dousing the exterior of the bottles 9 9. Lid 2 is then lowered and 100 fastened by means of latch 41. The bottles 9 9 now being secured in the revolving frame 4, water is turned into the stationary pipe 39 and passes through the hollow tube 7 into

the flexible tube 19, through pipe 20 into branch connections 18 18, through exit-pipes 13 13, into shot-boxes 11 11, and bottles 9 9. The shaft 7 is given a half-turn, which 5 changes the position of the bottles 9 9 to the reverse, as shown in Fig. I, and while the bottles 9 9 remain in that position, with their heads up, the shot 12 12 will fall into them. Power is transmitted by a belt through the 10 keyed pulley-wheel 31 to the hollow shaft 7, turning the frame 4 and carrying the bottles 9 9 around with the hollow shaft 7. While the hollow shaft 7 is revolving it also receives a longitudinally-reciprocating movement by 15 means of the double cam 29 and spiral spring 36, forcing the cam 37 inwardly, where it meets the serrations 29°. The longitudinal axes of the bottles 9 9 do not coincide with lines radiating from the shaft 7 as a center. 20 The action of centrifugal force in lodging the shot 12 12 at the bottoms of the bottles 9 9 would occur on a true swing around the axle, while in my device the shot is greatly agitated and is thrown with force against the 25 sides and bottoms of the bottles 9 9, causing a scouring or scrubbing off of the film of starchy substance and such refuse as is usually found in bottles to be refilled. While the interior portions of the bottles 9 9 are 30 being scrubbed the exterior portions are being repeatedly doused in water contained in the tank 1, preferably up to the level of the shaft 7. After the bottles 9 9 have been shotted and left in the position shown in 35 Fig. III lids 2 and 5 are raised. In the meantime the shot 12 12 have fallen into their holder 11 11 and the bottles are ready to be rinsed.

By referring to Fig. IV and assuming the levers to be in position as indicated by the 40 dotted lines, which position would be the same for all parts, as described in Figs. I or III, the operator draws the lever-bar 21 over to the position indicated by full lines. The 45 said movement of lever-bar 21 causes the side lever-arms 22 22 to turn shafts 24 24 through their connections, crank-arms 23 23, causing cranks 25 25 to move upwardly, lifting the hangers 26 26. The hangers 26 26 through the supports 27 27, attached thereto under 50 the branch pipes 18 18, raise the said branch pipes 18 18 and their connection, while still permitting the water to flow through them by means of the flexible tubular connections 19. The exit-pipes 13 13 enter the necks of 55 the bottles 9 9, and the flow of the water from

said exit-pipes 13 13 thoroughly rinses the interiors of the bottles 9 9. When the lever-bar 21 is drawn to the position as indicated by full lines through the same means as heretofore described, it also brings into contact 60 with the bottoms of the racks 8 8 lifters 44 44, which raise the racks 8 8, said racks carrying the bottles 9 9 upward until their heads are out of the mouths 11' 11' of the shot-holders 11 11, which permits the bottles to be more 65 thoroughly rinsed. After the bottles are rinsed the water-supply is cut off, lever-bar 21 reversed to its nominal position, racks and bottles removed, and the machine is ready 70 for its next charge. I have also provided 70 means for closing the exit of the shot-holders 11 11 to keep the shot 12 from falling out of the holders 11 11 when necessary to repair the machine. I do not, however, limit my invention to the shot-holders 11 11 being open 75 while the machine is in operation, for, assuming the lid 2 to be raised and the bottles held in position, as shown in Fig. III, and the water passing into bottles 9 9, by making a half-revolution of the frame 4, bringing the 80 bottle-neck upward, the shot 12 would pass into the bottles 9 9. Then by turning lever-handle 17' it would turn shaft 17 and cause lever 16 16 to slide the valve 15 15, closing ports 15', keeping the shot and water in the 85 bottle while being shotted.

I do not limit my invention to the exact means and methods described; but

What I desire to claim, broadly, is—

1. In a bottle-washing machine, a tank, a 90 shaft revolving in said tank, a frame attached to said shaft carrying shot-holders, and means for securing bottles thereto parallel with a plane of the axis of said shaft and in engagement with the shot-holders, and for raising 95 them out of the mouths of said shot-holders.

2. In a bottle-washing machine the combination of a tank; a rotatable hollow shaft secured in said tank; a frame secured on said shaft; a rack secured in said frame; a shot-holder secured in said frame; a pipe guided in said shot-holder, a flexible coupling between said hollow shaft and said pipe and means for raising and lowering said pipe. 100

Signed at Pittsburg, Pennsylvania, this 105
23d day of August, 1900.

JOHAN GEORGE HIEHR.
